UNITED STATES PATENT OFFICE.

ARTHUR S. KNIGHT, OF NEWARK, NEW JERSEY, ASSIGNOR TO WESTINGHOUSE LAMP COMPANY, A CORPORATION OF PENNSYLVANIA.

INCANDESCENT LAMP.

1,059,737.

Specification of Letters Patent.

Patented Apr. 22, 1913.

Application filed May 13, 1909. Serial No. 495,788.

To all whom it may concern:

Be it known that I, ARTHUR S. KNIGHT, a subject of the King of Great Britain, and a resident of Newark, in the county of Essex and State of New Jersey, have invented a new and useful Improvement in Incandescent Lamps, of which the following is a specification.

My invention relates to incandescent lamps, and particularly to lamps having very long, fine filaments, such as filaments composed of, or containing, tungsten.

The object of the invention is to provide a lamp the construction of which shall be such that the lamp may be more expeditiously and economically manufactured than other lamps heretofore provided, and in which the filament shall be so mounted that it may withstand severe shocks and vibration without breakage. One of the modifications of the lamp is also adapted to give the greatest candle power when viewed "end on."

Owing to the difficulty that has heretofore existed of producing tungsten and similar very fine filaments in considerable lengths, or in lengths sufficient for the complete circuit within a lamp, the filaments have been made into short lengths of U or hair-pin shape and have been mounted by fusing their extremities together and to supporting members therefor. The filaments have thus been rigidly supported at intervals of their lengths, with the result that they have been particularly subject to breakage at or near these points of support, upon the occurrence of shocks and vibration. Moreover, the fusing of the filament very often weakens it. Means have now been provided, however, by others than myself, for producing filaments continuously and in great lengths, and, instead of cutting the filament into short lengths and bending them into U or hair-pin shape, I propose to make the entire filament within the lamp continuous between the terminal-supporting members, to which alone it is secured by fusing or otherwise, the filaments being loosely supported at intermediate points.

Figure 1 of the accompanying drawing is a perspective view of the internal parts of a lamp constructed in accordance with the present invention. Fig. 2 represents a modification of a portion of the structure of Fig.

1 and Fig. 3 is a perspective view of a modification of the lamp of Fig. 1.

In Fig. 1, an arbor 1 that is mounted upon a stem 2 is provided with two sets of wire or other suitable projecting supporting members 3, the free ends of which are hook-shaped, two of the supporting members 4 and 5 being extended downwardly through the stem 2 and forming terminals for the lamp. A filament 6 extends, in zig-zag form, between the terminal-supporting members 4 and 5, to which it is fused or otherwise suitably secured, and it is looped about and supported upon the hook-shaped extremities of the supporting members 3. The filament may be simply bent or looped but once around the supporting members 3, as shown in Fig. 1, or it may be looped twice around the supports to form nearly two convolutions surrounding the same, as shown in Fig. 2.

A modification of the lamp is illustrated in Fig. 3, in which a short arbor 7 having a flattened end carries two sets of hooked supporting members 8 that project from opposite sides thereof and upon which the filament is mounted as in Fig. 1 and arranged in a plane which is substantially perpendicular to the axis of the stem of the lamp. With this arrangement, the lamp is adapted to give the greatest luminosity when viewed from its end or toward the end of the arbor.

As the filament in the present lamp is rigidly secured only at its extremities to the supporting members therefor, and merely passes over or loosely surrounds the remaining supporting members, it is specially adapted to sustain severe shocks and vibration without breakage, and, since it is continuous between the terminal-supporting members, it is more readily applied to the mounting than the short pieces of filament of U or hair-pin shape, which have been heretofore commonly employed.

I claim as my invention:

1. An incandescent lamp comprising an arbor, a plurality of hook supporting members projecting therefrom and arranged in groups upon opposite sides thereof, and a filament extending in zig-zag form between the supporting members in a plane substantially normal to the axis of the arbor.

2. An incandescent lamp comprising an

arbor, a plurality of supporting members carried thereby, and a single filament extending between the supporting members in a plane that is substantially normal to the axis of the arbor.

3. An incandescent lamp comprising a single reversely bent filament the legs of which occupy a plane that is substantially normal to the axis of the lamp.

10 4. An incandescent lamp comprising a single reversely bent filament occupying a plane that is substantially normal to the axis of the lamp.

5. An incandescent lamp comprising a reversely bent filament the legs of which are substantially normal to the axis of the lamp.

15 6. An incandescent lamp comprising leading-in wires, a filament support, and a filament carried by the leading-in wires and the support and having its extremities coiled around the leading-in wires.

7. An incandescent lamp comprising leading-in wires, and a filament that is coiled around the leading-in wires.

20 25 8. An incandescent lamp comprising leading-in wires, and a filament extending continuously in zig-zag formation between the

leading-in wires and having its ends coiled around the leading-in wires.

9. An incandescent lamp comprising a 30 filament support, and a reversely bent filament carried by the leading-in wires and the support and having its ends coiled around the leading-in wires.

10. An incandescent lamp comprising an 35 arbor, leading-in wires extending therethrough, a filament support carried by the arbor, and a filament extending between the leading-in wires and the said support in a plane that is substantially normal to the 40 axis of the arbor.

11. An incandescent lamp comprising an arbor, a plurality of supporting members carried thereby, and a single, continuous, reversely bent filament located substantially 45 wholly in a plane substantially normal to the axis of the lamp.

In testimony whereof, I have hereunto subscribed my name this 30th day of April, 1909.

ARTHUR S. KNIGHT.
